UNITED STATES PATENT OFFICE.

DANIEL D. CURTIS, OF SIDNEY CENTRE, NEW YORK.

DEVICE FOR SECURING BEDSTEAD-RAILS TOGETHER.

SPECIFICATION forming part of Letters Patent No. 601,503, dated March 29, 1898.

Application filed October 12, 1897. Serial No. 654,930. (No model.)

To all whom it may concern:

Be it known that I, DANIEL D. CURTIS, a citizen of the United States, residing at Sidney Centre, in the county of Delaware and State of New York, have invented a certain new and useful Improvement in Devices for Securing Bedstead-Rails Together, of which the following is a specification.

My invention relates to a new and useful improvement in devices for holding bedstead-rails together for shipment or storage, and has for its object to provide an exceedingly simple and effective device of this description which consists, primarily, of notching the joint-irons of the rail and forming holes therethrough and then providing tie-plates for engagement with these joint-irons and pins for holding the plates in position.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawings, forming a part of this specification, in which—

Figure 1 is a perspective of the ends of the bedstead-rails placed side by side and secured together by means of my improved tie-plate; Fig. 2, one end of such a rail having a portion thereof sectioned away so as to show the arrangement of joint-irons and the relative position of the tie-plate when in engagement therewith; Fig. 3, a side view of another form of joint-irons with which my improvement may be combined, and Fig. 4 a perspective view of the tie-plate.

In carrying out my invention as here embodied, A represents the joint-irons, which may be of any suitable design and secured within the ends of the rails B so as to project beyond the latter, for the well-known purpose of securing said rails to the head and foot posts of the bedstead, and in the upper portion of these joint-irons I form notches or shoulders C, just beyond the face of the end of the rail, and also form holes D in the lower portion thereof at a slight distance from the

end of the rail, for the purpose hereinafter set forth.

A tie-plate E, as shown in Fig. 4, is formed of thin metal, such as sheet iron or steel, and has therein the slots F. These slots are of a width and length adapted to pass over the joint-irons, as clearly shown in Figs. 1 and 2, and when so engaged with said irons it will be seen that the rails will be firmly held against displacement relative to each other. In order that the tie-plates may not be accidentally disengaged from the joint-irons, pins G are passed through the holes D, and these pins are preferably wedge shape in order that they may be driven tightly within said holes, and these pins, in connection with the engagement of the upper edges of the slots with the notches C, will securely retain the tie-plates in position.

It is to be noted that the tie-plates may be made of any size and the slots therein carried any distance apart to suit the requirements of the particular rails that are to be secured together, as rails of various designs necessitate the variance of the distance between their joint-irons to prevent them from chafing.

Any inconvenience which has heretofore been experienced in securing together the side rails of a bedstead for shipment or storage has caused much annoyance and loss of time, as well as the marring of the surfaces which are left loose to chafe together; but my improvement entirely overcomes this disadvantage and securely holds the rails in place relative to each other, and yet the tie-plates may be quickly removed, so as to separate the rails when occasion requires. The form of joint-irons shown in Fig. 3, while somewhat different in outline from that shown in the remaining figures, nevertheless serves all the purposes for the utilization of my improved tie-plate; but I do not wish to limit the use of my improvement to any particular design of joint-irons, since it is obvious that it will work with equal facility in connection with joint-irons of various designs.

Having thus fully described my invention, what I claim as new and useful is—

1. The herein-described combination of the joint-irons of bedstead-rails, each of said irons

having a notch and a hole therein, and a tie-plate having slots therein adapted to pass over said joint-irons, enter into engagement with the notches, and means for securing said plate whereby the slots are held in engagement, substantially as shown and described.

2. The herein-described combination of two joint-irons carried by bedstead-rails, said irons having notches formed in their upper edges, and holes formed in their lower portions, a plate having two slots therein adapt-

ed to pass over the joint-irons and enter into engagement with the notches, and pins adapted to be forced within the holes for securing said tie-plates in position, as specified. 15

In testimony whereof I have hereunto affixed my signature in the presence of two subscribing witnesses.

DANIEL D. CURTIS.
